Comline and Russell, his Atty

UNITED STATES PATENT OFFICE.

ADDISON A. POTTER, OF SOUTH OTSELIC, NEW YORK.

TACK-HAMMER AND TACK-HOLDER.

SPECIFICATION forming part of Letters Patent No. 293,516, dated February 12, 1884.

Application filed September 10, 1883. (Model.)

To all whom it may concern:

Be it known that I, ADDISON A. POTTER, of South Otseelic, in the county of Chenango, and in the State of New York, have invented 5 certain new and useful Improvements in Tack-Hammers and Tack-Holders; and I do hereby declare that the following is a full, clear, and exact description thereof, reference being had to the accompanying drawings, making a part 10 of this specification, in which—

Figure 1 is a perspective view of my device as arranged for use. Fig. 2 is a longitudinal section of the hammer upon line $\alpha\alpha$ of Fig. 1, and Fig. 3 is a cross-section of the handle upon 15 line zz of said figure.

Letters of like name and kind refer to like parts in each of the figures.

The design of my invention is to furnish a cheap and convenient means whereby tacks 20 may be stored before using, and each tack may be held upon or within the hammer-face while being driven; and to this end said invention consists, principally, in the means employed for storing the tacks in convenient position for 25 use, substantially as hereinafter specified.

It consists, further, in the means employed for holding a tack upon the face of the hammer while being driven, substantially as hereinafter shown.

30 In the carrying out of my invention one or more longitudinal grooves, a , are formed in the handle A of my hammer B , which grooves have a T shape in cross-section, and extend from said hammer to a point near the opposite end of said handle, and at each end are provided with an enlargement, a' , that in diameter equals the width of the undercut portion. The outer narrow portion of each 35 groove a has a width somewhat greater than the greatest diameter of the body of the tack C that is to be used, while the undercut portion of said groove has a width and a depth somewhat greater than the diameter and thickness, respectively, of the head c of said tack, 40 the construction of said groove being such as to permit of the introduction of tacks into the same with their heads contained within said undercut part and their bodies projecting outward through the said narrow part. The 45 tacks C are introduced into the groove a through the enlargement a' at its outer end,

and are prevented from falling out of the lower end of said groove by means of a rubber band, E , which encircles the handle A where it enters the hammer B , and covers the 55 enlargement a' at such point. A second rubber band, D , placed around said handle and pressed downward against the outermost tack, prevents said tacks from moving toward and falling out of the upper end of said groove. 60 The tacks C thus confined within the groove a may, one at a time, be easily removed therefrom by grasping the body of the lowermost tack with the thumb and forefinger and pressing the same toward the hammer B , and at the 65 same time tilting the point of said tack toward said hammer, so as to release its head c from said groove.

Any desired number of grooves may be provided in the handle, and, if desired, such differences in size had as to enable any of the usual sizes of tacks to be accommodated.

In order that tacks may be held upon the face b of the hammer B in position for driving, a flat spring, F , is secured upon one side 70 of said hammer, with its end in a line with the end of the same. The outer or free end, f , of the spring F has a slight inward curve, and immediately adjacent thereto, within the face b , is formed a diagonally-arranged recess, b' , which has its inner side undercut, as shown in Fig. 2. Said undercut side is opposite to the inward-curved end f of said spring F , and in cross-section the space thus inclosed has a dovetailed form, while in plan 80 view said space has a wedge shape. If, now, the head c of the tack C is placed upon the bottom of the recess b , with the body of said tack in a line with the axis of the hammer B , and is then moved toward the narrowest end of said recess, said head will be securely confined between the undercut side of the latter and the spring F , and will be held with equal firmness against the bottom of said recess, in which position, by one blow of said 90 hammer, said tack may be driven to place, and by such operation is instantly released from engagement therewith.

Having thus fully set forth the nature and merits of my invention, what I claim as new 95 is—

1. As an article of manufacture, a hammer

having its handle formed with one or more T-shaped grooves adapted to receive and hold the head portions of a number of tacks, substantially as and for the purpose set forth:

5 2. The handle A, provided with the T-shaped groove *a*, having at each end an enlargement, *a'*, in combination with the elastic bands D and E, substantially as and for the purpose shown.

10 3. The hammer B, provided within its face *b* with the diagonal undercut recess *b'*, in com-

bination with the spring F, having an inward-curving outer end, *f*, substantially as and for the purpose set forth.

In testimony that I claim the foregoing I 15 have hereunto set my hand this 6th day of September, 1883.

ADDISON A. POTTER.
